UNITED STATES PATENT OFFICE.

EMIT A. KIRKENDALL, OF BAKER, OREGON

STAPLE.

1,024,008.

Specification of Letters Patent.

Patented Apr. 23, 1912.

Application filed March 15, 1911. Serial No. 614,668.

To all whom it may concern:

Be it known that I, EMIT A. KIRKEN-
DALL, a citizen of the United States, resid-
ing at Baker city, in the county of Baker
5 and State of Oregon, have invented certain
new and useful Improvements in Staples;
and I do hereby declare the following to be
a full, clear, and exact description of the
invention, such as will enable others skilled
10 in the art to which it appertains to make
and use the same.

My invention relates to new and useful
improvements in staples and more partic-
ularly to that class adapted to be used for
15 holding fence wires in engagement with the
post and my object is to provide an elong-
ated head on the closed end of the staple
so that the staple can be readily driven into
or removed from the post, and, a further
20 object is to provide a reinforcing section
for said head.

Other objects and advantages will be
hereinafter set forth and pointed out in the
specification.

25 In the accompanying drawings, which
are made a part of this application, Figure
1 is a perspective view showing the staple
applied to use. Fig. 2 is a side elevation of
the staple, and, Fig. 3 is an edge elevation
30 thereof.

Referring to the drawings in which simi-
lar reference numerals designate corre-
sponding parts throughout the several
35 views, 1 indicates a staple, which is of the
usual formation, and 2 indicates the neck
formed integral with the closed end 3 of the
staple.

Formed integral with and extending a
40 distance on each side of the neck is a head
4, that face of the head adjacent the staple
being tapered to increase the thickness of
the head at its juncture with the neck,
thereby providing a reinforcing section
45 on opposite sides of the neck.

In applying the staple to use, it is placed 45
over the wire 6 in the usual manner and the
points driven into the post 7 by delivering
blows on the head 4, said head providing
a convenient surface upon which to deliver
50 the blows.

If it should be desired to remove the sta-
ple, it can be readily accomplished by in-
troducing any suitable object between the
post and head and directing outward pres-
sure thereon and although the strain may 55
be at one end of the head, yet it will be pre-
vented from breaking off at its juncture
with its neck by providing the reinforcing
section.

This form of staple is peculiarly adapt-
able for use in parts of the country where
long stretches of wire fences are used, from
the fact that the staples can be quickly
withdrawn from the post and the wires dis-
posed on the ground for a distance so that 60
a team can be driven across the wires, there-
by saving the travel of a number of miles
to reach the end of the fence, and, it will
likewise be seen that the staples can be
65 quickly introduced into place to again se-
cure the wires to the post.

What I claim is:

A staple having a neck integral with the
curved portion thereof and flattened upon
opposite sides, and a head integral with the 75
neck portion and extending transversely
for some distance in opposite directions be-
yond the flattened sides of the neck, said
head being of circular form in cross section
and beveled outwardly from the flat sides 80
toward the opposite ends of the head.

In testimony whereof I have signed my
name to this specification in the presence of
two subscribing witnesses.

EMIT A. KIRKENDALL.
